UNITED STATES PATENT OFFICE.

JULIUS E. KARL, OF PEORIA, ILLINOIS.

VEHICLE-TOP.

1,371,626.

Specification of Letters Patent. Patented Mar. 15, 1921.

Application filed July 6, 1917. Serial No. 179,080.

To all whom it may concern:

Be it known that I, JULIUS E. KARL, citizen of the United States, residing at Peoria, in the county of Peoria and State of Illinois, have invented certain new and useful Improvements in Vehicle-Tops; and I do hereby declare that the following is a full, clear, and exact description of the invention, which will enable others skilled in the art to 10 which it appertains to make and use the same.

This invention relates to vehicle tops. It relates more particularly to a form of folding top for vehicles which will be semi-automatic in its action in that in being lifted to its extended position over the vehicle the slight manual effort required will be assisted by certain parts to carry said top to its said extended position.

20 Besides having for one of its objects to furnish a top of the "one man" type, the primary object of the invention, therefore, is to provide a top for vehicles with certain elements of such a nature that they will 25 practically carry said top to its extended position for use after being slightly raised from its folded position.

Another object is to provide certain elements in combination with the parts of a 30 folding top to automatically carry the several parts of the top to their normal positions when the top is being extended for use.

Certain advantages, also, will appear 35 from the following specification, aided by the accompanying drawing, which shows one embodiment of my invention, it being understood that changes may be made such as will lie within the meaning and intent of 40 the invention and within the scope of the appended claims.

Figure 1 is an elevation of a vehicle top, the fabric being in section, showing my improved top-supporting portion applied 45 thereto.

Figure 2 is an elevation of the top in the act of folding, the covering fabric not being shown.

Fig. 3 is a plan of certain parts illustrated in Fig. 1.

Fig. 4 is a longitudinal section of one of the parts of the folding top, and a companion part pivoted thereto.

Fig. 5 is a plan of portions of the same, 55 part being shown in horizontal section; and, Fig. 6 shows, enlarged, and in perspective,

certain jointed parts illustrated in Figs. 4 and 5.

1 indicates a horizontally disposed rail secured in any suitable manner to each side of the body of the vehicle, but one of which is shown, each having a slidable sleeve 2. Pivoted to the sleeve is a "socket" 3 carrying a bow 4, the socket and bow standing in a nearly upright position and placed far enough to the rear that it will not obstruct the view of persons in the rear seat.

5 is a link pivoted at one end to a part of said socket and at its other end to a fixed sleeve 5' or other suitable portion secured on the rail, but said link may be pivoted to the rail itself, if desired, 5² being a contractile spring on the rail and attached at its ends to the two sleeves 2 and 5' for example.

7 is a rail secured to and spaced from the side of the socket 3, whose purpose will be made known as the description proceeds.

The top structure comprises a series of members of "lazy-tongs" construction, 8 indicating a tubular member or socket, one end being pivotally attached to a sliding sleeve 9 on the rail 7, its other end being pivoted to one end of a rod-member 10, the other end of the latter pivoted in turn to a tubular member or socket 11 provided with a bow 12 at its forward end. 13 is a member pivoted at its forward end to a tubular member or socket 14. Said members 13 and 8 cross one another at substantially the middle of their lengths and are pivotally related. The rear end of the member 13 is provided with a bend forming an angular short arm 16. Substantially at its said bend the arm is pivoted to a bracket 17 extending from the forward face of the socket 3 and to the free end of the said arm 16 is pivoted a link 18 which in turn is pivoted to a short bow 19 at the rear of and pivoted at its lower end to the socket 3.

The socket 14 and the member 10 are pivoted at substantially the middle of their lengths and cross one another, and 20 is a link pivoted at its ends to the said socket 14 and the socket 11 substantially as shown in Fig. 1.

21 is a bow pivotally carried at the junction of the socket 8 and member 10. Preferably this bow extends below the pivot, as shown in Fig. 1, and has a stud 22 extending therefrom to engage beneath the member 10 in the folding operation, as shown in Fig. 2.

The entire top fabric carrying structure and the socket 3 are rigid with respect to one another, the whole being supported in rigid position through the rail 1 and the link 5 described. The spring 5² in the position shown in Fig. 1, when closed between the fixed sleeve 5' and the slideable sleeve 2, constitutes a stop for the latter preventing further movement thereof toward said sleeve 5'.
10

In addition to the peculiar arrangement of the bows 19 and 21 my improved structure will now be made known.

I have stated that the parts 8, 14 and 11
15 are tubular. This form is provided in order that each may contain a contractile spring for assisting in moving the top to its extended position shown in Fig. 1.

In Fig. 4 one of these tubular sockets, or
20 that corresponding to 8, for example, is shown in longitudinal section but is that socket at the opposite side of the top as it would appear to an occupant of the vehicle.

25 23 is a casting secured in one end of the bow for attachment to the sleeve 9, its inner end having an eye or other suitable portion 24 to which is connected one end of a contractile spring 25. In the opposite end of the tube is inserted a casting 26 having a
30 bend and provided with a shoulder 27. The companion member 10 in which the tube is associated may be merely a flat bar and has a corresponding oppositely formed bend which is pivoted to the said casting 26 at
35 28. The bent portion of the member 10 includes a finger 29 extended beyond its pivot as best shown in Fig. 6, and also has a shoulder 30 to abut upon the shoulder 27 as shown in that figure.

40 31 is a member connected to the finger 29 with the described spring 25. Those ends of the members 13 and 14 that are pivotally connected and those ends of the member 10 and socket 11 that are also pivotally connected are constructed in the same manner.

45 The described casting 26, as shown in Fig. 5, has a longitudinal opening 32 through which the said member 31 extends. It is observed that when the socket 8 and the member 10 are folded together, as in Fig. 4, and this is true of the other joints mentioned above, the finger 29 moves away from the casting 26 toward the opposite side of the pivot point thereby stretching the spring to a considerable extent and in the folded position, the member 31 being brought close to the pivot 28, prevents the spring from exerting a pull sufficient to move the parts from the folded position.
50

60 That is to say, the pull of the combined springs contained in the sockets 8, 14 and 11 at each side of the top are not sufficient to cause said top to lift when in the folded position.

65 The abutting shoulders 27 and 30 are pro-

vided in order that the top will not be extended farther than that shown in Fig. 1, the springs being prevented from drawing the joints of the various parts closer together, the various sockets and the members crossing them always bearing the same relation to one another in the extended position. The springs in the sockets 14 and 11 are attached to the ends of the bows 15 and 12 respectively by screw eyes or other devices
70 attached to the latter (but not shown) making a form of attachment substantially the same as the attachment of the spring in the socket 8 described when attached to the eye 24.
75

The pivots for the sockets 8, 14 and 11 and their members 13, 10, 20 where they cross are substantially as shown in Fig. 5 wherein 32' is a plate that may be secured to each of the several sockets, there being
80 a stud 33 extending therefrom to take the said members. By this arrangement or its equivalent the interior of the socket will not be obstructed by passing a rivet or other part through it.
85

90 In folding the top down to the position shown in Fig. 2, the sleeve 9 is moved down upon the rod 7 at the same time of course moving the top rearwardly. The point of connection of the link 5 with the socket 3 at
95 this time causes the sleeve 2 to move forward upon the rail 1 thereby drawing out the spring 5² thereby placing it under tension. The weight of the top and the downward pull by the attendant will cause said spring
100 to be fully stretched and, as the link 5 and the socket 3 will lie practically parallel to one another so that the pivot points at the ends of the links and the pivot point of the bow 3 on the sleeve 2 will be practically in
105 line, the springs cannot exert a pull sufficient to raise said top.

110 As the parts assume the folded position the various sockets and the cross members pivoted to them will reverse their position,
115 all of the springs 25 being placed under strain as already described, the top retaining its said position by its own weight. It is observed by a study of Fig. 2 that the arm 16 of the member 13 assumes a position perpendicular to the socket 3 where in the raised position it is parallel to it, and its movement to this position draws the short bow 19 close up beneath the socket 3 and bow 4 automatically.
120

The described stud 22 on the bow 21 engages beneath the member 10 and thus supports said bow parallel to the other members of the structure.

125 In restoring the top to its raised or extended position the bow 3 is raised assisted by the spring 5² and as the sleeve 9 approaches the outer or upper end of the rod 7 and the fingers 29 are moved so that the springs 25 can exert a pull, the entire top
130

will be carried forward without effort on the part of the attendant, the bow 21 rising to its upright position due to the pull of fabric thereon and automatically the bow 19 is moved rearwardly to its open position in Fig. 1, the top being supported upon the wind-shield or any other desired member. In the absence of the spring 52, if not used, the top is raised by manual effort alone but since the springs 25 exert themselves the moment the line of their pull is moved away from the pivots 28, the top being at once extended acts as a lever whose weight being thrown forward of the supports for the socket 3 readily restores the whole structure to position for use. Suitable means may be provided on the rail for limiting the rearward movement of the sleeve 2.

By distributing the several springs throughout the structure each is separately in control of pairs of members. Thereby said springs are required to be only of such strength individually that when operating in conjunction the combined forces are sufficient for proper work.

The springs are then not in danger of breaking as would likely result when but one is used and made strong enough to do the work of several. Furthermore, the manipulation of the top is more smooth and positive in any of its positions.

As already intimated, slight changes may be made in the construction of my improved top, all of which will be suggested to the mind of the practical person.

Having thus described my invention, I claim:

1. In combination with a vehicle body, a foldable top including in its construction a lever comprising connected members forming a truss, a standard carrying one of the members of the rear end of the truss including a guide upon which one of the other members of the truss is slidable, the standard and guide acting to suspend the truss in its extended position, a rod mounted horizontally upon the vehicle upon which the

standard is supported and above which it is adapted to move, a spring engaging the standard constantly tending to carry the same to its upright position, a link connected to the standard adapted to limit the movement of the same upon the rod, and a series of springs connected between members of the pairs of members of the truss constantly tending to project the truss to its extended position over the vehicle body.

2. In combination with a vehicle body, a rail mounted in a horizontal position thereon, a fabric carrying structure, a support to carry the same slidably mounted on said rail, a link pivoted at one end relatively to the body and at its other end to the support at a point spaced from its slidably mounted end, and a spring operatively engaging the support acting to move the same in the direction of the link.

3. A foldable vehicle top including in its construction pairs of members pivotally connected forming a lazy-tongs, one of the members of each pair at its end having such connection including a part extending beyond its pivot substantially in line with the longitudinal line of the other member of the pair, a spring connected at its ends to the said part and said other member, the line of pull of the spring in the folded position of the top lying substantially across the pivot, a standard carrying the lazy-tongs, a member supported horizontally upon the vehicle, the standard having slidable engagement with it, a link pivotally connected at one end to the standard and pivoted at its other end with respect to the last named member, and a contractile spring fixed at one end relatively to the said member, its other end being operatively connected to the said standard.

In testimony whereof I affix my signature, in presence of two witnesses.

JULIUS E. KARL.
